LAMP

Leo S. Greenmun, Syracuse, N. Y., assignor of
one-half to R. Walter Richman, Tully, N. Y.,
and one-half to Dayatnite Lamp Corporation,
a corporation of Delaware

Application October 3, 1933, Serial No. 691,953

4 Claims. (Cl. 240—48.6)

This invention relates as indicated to lamps, but has reference more particularly to automobile headlamps and means for controlling the forwardly directed rays from the bulb filament or other light source in such bulb so as to prevent glare and other ill effects by causing substantially all of these rays to be properly re-directed and projected as reflected rays which lie in the main beam of the headlamp and assist in properly illuminating the roadway in advance of the automobile.

It is a primary object of the present invention to provide an auxiliary reflector which will occupy only a small portion of the space between the bulb and lens of the headlamp, which will reflect the direct rays emanating from the light source in such a manner as to cause a minimum amount of heating of the filament and which will uniformly distribute such direct rays over a large portion of the surface of the main reflector. Another object of the invention is to provide an auxiliary reflector which is so disposed with reference to the light source as to effectively control substantially all of the direct rays from the filament, and none of these rays will be lost or scattered.

To the accomplishment of the foregoing and related ends, the invention, then, consists of the means hereinafter fully described and particularly pointed out in the claims; the annexed drawing and the following description setting forth in detail a device exemplifying my invention, such disclosed device constituting however, but one of the various applications of the principles of my invention.

In said annexed drawing:

Fig. 1 is a cross-sectional view through a conventional type of automobile headlamp showing the auxiliary reflector employed as an attachment for the bulb and Fig. 2 is a perspective view of the auxiliary reflector shown in Fig. 1.

Referring more particularly to the drawing, there is shown a lamp of conventional form comprising an outer casing or shell 1 within which is mounted a parabolic main reflector 2 having an axially disposed socket 3 within which is received the base 4 of the bulb 5. The filament 5a of the bulb is disposed at substantially the focus of the main reflector 2. The auxiliary reflector comprises a hollow sheet metal cone 6 having a highly polished interior surface 7, the cone being provided with circumferentially spaced base extensions 8 which are bent around an annular wire support 9. The support 9 is provided with integral rearwardly extending bracket

arms 10, which diverge as at 11 and are bent upwardly to provide semi-circular clamp members 12 and 13 which are adapted to engage the base 4 of the bulb 5. The clamp member 12 is provided with a locking link 14 which is adapted to engage the hook-like end 15 of the clamp member 13 to maintain the clamp members in engagement with the base of the bulb, the clamp members being capable of being locked together in this manner only after they have been drawn together sufficiently by sliding the locking link 16 to the position shown in Figs. 1 and 2. The entire auxiliary reflector attachment may be removed without removing the bulb from its socket, this being accomplished by releasing the link 14 from engagement with the hook 15 and sliding the link 16 to the forward end of the bracket arms 10, whereupon the clamp members may be spread apart sufficiently to remove them from the base of the bulb. The attachment may likewise be accomplished in an obvious manner without removing the bulb from its socket. In previous auxiliary devices of this character it was necessary to remove the bulb from its socket before the device could be attached to or removed from the bulb.

It will be noted that the reflector cone 6 is disposed with its apex lying substantially in the focal axis of the main reflector, that the reflector extends rearwardly and partially encompasses the bulb 5, and that the base of the reflector lies in a plane parallel with and spaced sufficiently close to the focal plane of the main reflector 2, so that none of the forwardly directed rays from the filament 5a of the bulb, that is to say, none of those rays which emanate from the source of light in front of the focal plane of the main reflector, can pass directly out of the headlamp, and thus be lost or scattered. A ray R, for example, which is the foremost forwardly directed ray which can be projected in advance of the focal plane of the main reflector without intercepting the auxiliary reflector will strike the edge of the reflector. There will, therefore, be no scattered rays tending to create a hazy condition immediately in front of the automobile when driving in mist, fog, smoke or rain. The character of the illumination is such that the image produced on a screen by the headlamp is not distorted but substantially the same as an image produced without the auxiliary reflector. The highly polished interior surface 7 of the auxiliary reflector is effective to cause substantially all of the aforesaid forwardly directed rays from the bulb filament to be so reflected onto the main reflector that they will be projected from the

lamp as part of the main beam, thereby securing a proper illumination of the roadway in advance of the automobile. The shape of the reflector surface 7 is such that an inconsequential number 5 of the direct rays from the filament will be reflected back to the light source, and an undue heating effect is thus avoided.

It is thus seen that I have provided an auxiliary reflector for automobile headlamps and the like 10 which effectively controls substantially all of the direct rays from the bulb filament and which effectively reflects substantially all of the direct rays back to the main reflector and produces no substantial heating effect in the vicinity of the 15 bulb. The reflector is particularly useful in eliminating glare which would normally be produced by the rays emanating from the filament in line with the focal axis of the main reflector and also eliminates haze produced by rays which, in some 20 lamps employing auxiliary reflectors are caused by the direct rays passing out of the headlamp beyond the base of the conical auxiliary reflector.

This application is a continuation-in-part of my application Serial No. 589,665, filed January 25, 1932.

I therefore particularly point out and distinctly claim as my invention:—

1. An attachment for headlamp bulbs comprising a cone-shaped reflector, and a support therefor, said support comprising a wire bent into annular form and having angularly extending arms terminating in semi-circular loop portions, one of said loop portions being provided with a locking link and the other of said loop portions terminating in a hook-like end adapted to be releasably engaged by said locking link.

2. An attachment for headlamp bulbs comprising a reflector and a support therefor, said sup-

port comprising a wire bent into annular form intermediate its ends, arms extending from and at an angle to said annular portion, said arms being parallel and in engagement with each other for a portion of their length and parallel but 5 spaced apart for another portion of their length, said parallel portions being joined by diverging portions of the arms, semi-circular members extending from the spaced parallel portions of the arms and adapted to engage the base of a bulb to 10 which the reflector is attached and a link encompassing said arms and slidably therealong for causing said semi-circular members to approach each other.

3. In a headlamp ray control, a light bulb, a 15 reflector disposed in front of the light bulb, said reflector being a hollow body of cone-shape, spaced extensions carried by the base of the cone-shaped reflector, supporting means for the reflector comprising an annulus extending around the base of the reflector and engaged by the base extensions thereon, a pair of arms extending from the annulus and terminating in clamping means for engagement with the base of the bulb, and a slide for operating the clamping means.

25

4. In a headlamp ray control, a light bulb, a cone-shaped reflector disposed in front of the light bulb, spaced extensions carried by the base of the cone-shaped reflector, supporting means for the reflector comprising an annulus extending around the base of the reflector and connected thereto by the extensions thereon, a pair of arms extending side by side from the annulus and from one side only of the base of the reflector and terminating in clamping means for engagement with the base of the bulb, and a slide for operating the clamping means.
